UNITED STATES PATENT OFFICE.

FRANCIS HENRY CALLAHAN, OF NEW HAVEN, CONNECTICUT.

TOY.

1,366,115.

Specification of Letters Patent. Patented Jan. 18, 1921.

Application filed November 7, 1919. Serial No. 336,367.

To all whom it may concern:

Be it known that I, FRANCIS H. CALLAHAN, a citizen of the United States, residing at New Haven, in the county of New Haven and State of Connecticut, have invented certain new and useful Improvements in Toys; and I do declare the following to be a full, clear, and exact description of the invention, such as will enable others skilled in the art to which it appertains to make and use the same.

This invention relates to toys, and more specifically an improved toy which may hereafter be known as "goldfish pool" or "goldfish pond."

One object of the invention is to provide an improved game or puzzle comprising a chamber bearing a resemblance to a pool, one or more fishes in the pool, and a goal into which one of the fishes is adapted to enter.

Another object is to provide a device of this character in which the fishes are supported at different levels and can pass over and under one another.

Another object is to provide an improved toy of this character in which all the parts can be made and assembled at a slight expense, being made principally of paper or similar sheet material.

Other objects and advantages may become apparent to persons who read the following details of description in connection with the accompanying drawings in which:

Figure 1 is a perspective view illustrating my improved toy or imitation goldfish pool complete.

Fig. 2 is a somewhat enlarged longitudinal vertical sectional view.

Fig. 3 is a horizontal sectional view, the section being taken along the line 3—3 of Fig. 2.

Fig. 4 is a transverse vertical central sectional view.

Fig. 5 is a perspective view illustrating one of the toy-members which represent or imitate goldfish within the box which represents the pool.

Referring to these drawings in detail, in which similar reference characters correspond with similar parts throughout the several views,—

The invention comprises a box having an outer wall 1 which is formed of end and side sections arranged in angular relation to one another and supporting a transparent cover

2. An opaque floor 3 is inclosed by and secured to the lower edges of the outer wall sections, and a transparent upper floor 4 is supported between the cover 2 and floor 3 by means of upper and lower inner wall sections 5 and 6, respectively. Each of these inner wall sections comprises a strip of paper or other sheet material fitted against the inner surfaces of the outer wall sections and provided with curved portions 7 which are spaced from the corner recesses or internal corners of the outer wall. These inner wall sections 5 and 6 may be secured to the outer wall sections at points intermediate the corners of the latter, thereby adding strength to the box while securing the upper floor in its position substantially midway between the lower floor and cover, thereby providing upper and lower chambers of substantially equal dimensions. Moreover, these curved portions 7 prevent the imitation fishes or toy-members from entering the internal corners of the box, so that these corners cannot be utilized to assist in turning the fishes horizontally; whereby the internal curved walls render the puzzle more difficult to solve.

In the simplest form of my invention I may eliminate the lower chamber, and the invention may include only a single chamber, a single fish or toy-member 8 (such as shown separately in Fig. 5) and a single goal member 9, but in the form here described there are at least two of the members 8, one in the upper chamber and one in the lower chamber. However, more than two of the members 8 may be provided, as illustrated, and the members 8 of the lower chamber are visible through the transparent floor 4 as well as through the transparent cover 2, while the fish or fishes in the upper chamber are visible through the transparent cover 2 and appears to be floating in water over the fishes in the lower chamber. At times there is some difficulty in determining whether a certain fish is in the lower or upper chamber, and this increases the puzzling effect of the device.

Each imitation fish 8 is preferably formed of a plane blank of sheet material which is outwardly curved at opposite edges so as to form a relatively wide front portion, the rear portion being relatively narrow and preferably formed with concaved edges. This blank is formed with a sharp or abrupt straight bend extending from end to end

along its median line, and the two halves or side plates at opposite sides of this median line are turned at an angle of approximately 60 degrees to one another. Where 5 these members are formed of paper or cardboard, it is advantageous to secure the side plates in the desired angular relation to one another by means of a length of wire or rod 10 which serves as an axle for a spherical 10 roller 10^a, and these elements 10 and 10^a serve as a weight to propel and control the movements of the member within the box when the latter is turned in different directions or at different angles to the horizontal. 15 The outwardly curved or convexed edges 11 constitute runners somewhat similar to those of a sleigh, being upwardly and forwardly inclined at their front ends. This feature of the device enables its front end to extend 20 over and bear upon the goal member 9, which is downwardly and inwardly inclined as more clearly shown in Fig. 4. When the forward portions of the runners 11 thus bear upon the goal member, the box being 25 tilted in the direction of the goal member, the member 8 may be caused to enter the goal or notch of the member 9 by tilting the box in the direction of the end farthest from this member 8. However, the success of the 30 manipulator in thus causing the toy-member to enter the goal requires extreme care and skill in tilting the box to the proper angles, according to the exact position of the toy-member with relation to the goal. Moreover, the goal member 9 forms a shield to 35 hide the fishes in the lower chamber, and this feature may be taken advantage of to prevent confusion or optical illusion with reference to the upper and lower toy members. The upwardly and forwardly inclined edges of the runners 11 also simulate the head of a goldfish, and this simulation is improved by providing artificial eyes 12 which may be painted or printed on or attached to 40 the respective side plates. Moreover, the broad portions having the convexed edges combine to simulate the main body portion of a fish, while the relatively narrow rear portion 13 simulates the tail of a fish. The 45 runners 11 co-act, one at a time, with the roller 10^a, for supporting the fish in its upright position and permitting it to slide and roll on the floor as described herein-after. 50 When transparent paper is employed for forming the fishes or toy-members 8, the same may be gilded or tinted so as to simulate the coloring of real goldfish, and the rod 10 may be fixed to the side plates for retaining them in the proper relative position, as previously mentioned; but when sheet metal, celluloid or the like are employed for making the imitation fishes, the rod 10 may be rotatably mounted in the side 55 plates and have the roller 10^a fixed thereon. 60 65

Referring to the goal member 9, it will be seen that the notch 14 thereof, which constitutes the goal proper, is approximately the same shape and size as the cross sectional area of one of the imitation fishes, being 70 downwardly flared and only sufficiently large for the fish to easily enter when properly positioned in front of the notch 14 when the front end or head is elevated as shown in Fig. 2. The height of each chamber is but 75 slightly greater than the height of the fish when in its normal position shown in Fig. 2, and it is extremely difficult or impossible for one of the fishes to become inverted in either of the chambers because of its cross sectional angular formation, the inclined sides of the angle being wider than the distance between the floors or between the upper floor and cover. 80

The goal member 9 is preferably formed 85 of a blank of paper, celluloid or other sheet material, and this blank is formed with a horizontal upper portion 15 and a vertical flange 16, the latter being embraced between the outer wall 1 and the inner wall 5. When 90 this goal member is made of paper its upper portion 51 may be pasted to an upper inwardly extending flange 17 which supports the transparent cover 2, and the lower edge of the goal member may be pasted or 95 otherwise secured to the transparent floor 4. However, when the goal members are made of metal, celluloid or other sheet metal capable of having permanent set no paste or other securing means is necessary for securing 100 such member in place.

The outer wall 1, the bottom floor 3 and edge portions of the cover 2 may be covered with an outer lining 18 of cloth or paper in imitation of leather or the like, 105 and a carpet 19 of paper may cover the floor 3, this carpet being preferably oiled or glazed so as to permit the toy-members 8 to move noiselessly thereon.

From the foregoing description it should 110 be understood that the box having the transparent floor and cover is intended to simulate a pool or pond of water in which the fishes or toy-members 8 appear to swim at the different levels, this appearance of real 115 fishes in real water being a matter of primary interest to persons who enjoy toys, etc. Moreover, the difficulty and patience required in placing one of the imitation fishes in the goal enhances the value of the device 120 as an entertainer.

The imitation fishes are entirely protected 125 against contact with any and everything external of the box, so that they can not be moved except by manipulation of the box. When the box is tilted in different directions, each fish turns in different directions about the point of its spherical roller that touches the floor, thereby simulating the motions of actual fishes. This turning of the 130

fishes results from the location of the roller nearer the head than the tail, so that the weight and leverage of the latter tends to turn the tail down the incline and cause the 5 fish to move backward, but this tendency is sometimes overcome by the friction of one of the side plates against the floor. In this connection it should be understood that the roller 10^a is movable along its axis so that 10 either side plate or runner may frictionally engage with the floor. The curved edges 11 also permit a rocking motion of the fish about the shaft or axle 10.

Although I have described this embodiment of my invention very specifically, it 15 is not intended to limit this invention to these exact details of construction and arrangement, but changes may be made within the scope of the inventive ideas as implied 20 and claimed.

What I claim as my invention is:

1. In a toy, a chamber having a floor and a transparent cover, a goal in said chamber, a toy-member slidable on said floor and being adapted to enter said goal, said toy-member being formed of two plane downwardly diverging plates whose spaced edges serve as runners on which the toy-member slides, the said goal comprising a sheet having a downwardly flared notch in its lower edge through which said toy-member can pass, said sheet being secured in fixed relation to said floor by means of its upper edge portion.

2. In a toy, a chamber having a floor and a transparent cover, a goal in said chamber, a toy-member slidable on said floor and being adapted to enter said goal, said toy-member being formed of two diverging plates whose spaced edges serve as runners on which the toy-member slides, the front portion of each of these runners being forwardly and upwardly inclined, said goal comprising a sheet disposed in an inclined position and having a notch at its lower edge to receive said toy-member, whereby the front end of said toy-member can project over the goal-sheet and be controlled by the latter as specified.

3. In a toy, the combination of a chamber comprising a floor and outer walls arranged in angular relation to one another and extending up from said floor, a transparent cover on said chamber, an inner wall within 55 the outer wall and having outwardly

curved portions spaced from the corner-recess of the outer wall, said inner wall having portions fitting against the parts of the wall between the said corner recesses and holding said floor and cover in spaced relation to one another, a goal in said chamber, and a toy-member in said chamber adapted to enter said goal.

4. A traveling toy formed of a plane blank of sheet material having opposite outwardly curved edges forming a relatively wide portion adjacent to one end, the blank being formed with a straight abrupt bend along its median line and comprising two plane diverging side sections, the said curved edges thus forming runners on which this toy-member is slidable and rockable.

5. A traveling toy formed of a blank of sheet material having opposite outwardly curved edges forming a relatively wide portion adjacent to one end, the blank being bent along its median line to form two diverging side sections, the said curved edges thus forming runners on which this toy-member is slidable and rockable, and a rod having its ends secured respectively to said diverging side section and holding these sides in their diverging relation while serving as a weight to control movement of the toy-member.

6. A traveling toy formed with side plates having curved lower edges on which it slides alternately and on which it rocks, an axle carried by said side plates, and a roller carried by said axle between the side plates and extending downwardly beyond said curved lower edges, said roller being adapted to coact with said curved edges alternately for supporting the body of the toy member and permitting it to slide and roll on a floor or similar surface.

7. A traveling toy formed with side plates having lower edges on which it slides alternately, an axle carried by said sides, and a roller having a spherical tread and being disposed between said side plates and adapted to coact alternately therewith to support the body of the toy on a floor or similar surface, said roller being movable along its axis of rotation to effect the alternate coaction of said lower edges therewith.

In testimony whereof I have hereunto set my hand.

FRANCIS HENRY CALLAHAN.
